US00D729907S

(12) **United States Design Patent**
Castrigno et al.

(10) **Patent No.:** **US D729,907 S**
(45) **Date of Patent:** **** May 19, 2015**

(54) **END CAP PIPE FITTING**

(71) Applicant: **Watts Water Technologies, Inc.**, North Andover, MA (US)

(72) Inventors: **Steven Castrigno**, Manchester, NH (US); **Jeffrey A. Scilingo**, Londonderry, NH (US)

(73) Assignee: **Watts Water Technologies, Inc.**, North Andover, MA (US)

(**) Term: **14 Years**

(21) Appl. No.: **29/453,638**

(22) Filed: **May 1, 2013**

(51) **LOC (10) Cl.** **23-01**

(52) **U.S. Cl.**

USPC **D23/260**

(58) **Field of Classification Search**

(57) **CLAIM**

The ornamental design for an end cap pipe fitting, as shown and described.

DESCRIPTION

FIG. 1 is a perspective view of the end cap pipe fitting according to the present disclosure.

FIG. 2 is a top view of the end cap pipe fitting according to the present disclosure.

FIG. 3 is a bottom view of the end cap pipe fitting according to the present disclosure.

FIG. 4 is a side view of the end cap pipe fitting according to the present disclosure.

FIG. 5 is a side view of the end cap pipe fitting according to the present disclosure.

FIG. 6 is an end view of the end cap pipe fitting according to the present disclosure; and,

FIG. 7 is an end view of the end cap pipe fitting according to the present disclosure.

The broken lines are shown for the purposes of illustrating portions of the end cap pipe fitting and form no part of the claimed design.

1 Claim, 4 Drawing Sheets
